United States Patent Office.

JOSEPH BELL ALEXANDER, OF WASHINGTON, DISTRICT OF COLUMBIA.

Letters Patent No. 65,857, dated June 18, 1867.

IMPROVED STOPPERS FOR BOTTLES, JUGS, &c.

The Schedule referred to in these Letters Patent and making part of the same.

TO ALL WHOM IT MAY CONCERN:

Be it known that I, JOSEPH BELL ALEXANDER, of Washington, in the county of Washington, and District of Columbia, have invented a new and improved Mode of Constructing Corks or Stoppers for Bottles, Jugs, Jars, or Cans; and I do hereby declare that the following is a full, clear, and exact description of the construction and operation of the same, reference being had to the accompanying drawings, and to the letters of reference marked thereon, making a part of this specification, in which—

Figure 1 represents a vertical section through the cork or stopper, showing one method of construction.

Figure 2 represents a vertical section through the cork or stopper, showing another mode of construction.

Figure 3 represents a vertical section through the cork or stopper, showing a third mode of construction.

Figure 4 represents, in perspective, an external view of the neck of a bottle with the stopper inserted.

Figure 5 represents, in perspective, an external view of the neck of a beer or ale jug with the stopper inserted and held down by a wire clasp.

Figure 6 represents, in perspective, an isometrical view of fig. 5.

Similar letters of reference, where they occur in the several figures, denote like parts in all cases.

The nature of my invention consists in constructing a stopper for bottles, jugs, jars, or cans which can be easily drawn in a moment without a cork-screw, and which, when in place, will present no corrodible substance to the action of gases or liquors with which it is inserted and may come in contact; and also to so construct the stopper that it will bear continued use without becoming broken or lost.

To enable others skilled in the art to make and use my invention, I will proceed to describe its construction and operation.

I make the body A (see drawings) of my stopper of cork, India rubber, gutta percha, wood, or any other suitable material, in any of the known forms, externally. Longitudinally through the centre of this body A I make a bore which will admit a metallic rod or wire, C, with an eye or circle bent upon its upper end, and which is first passed through a hole countersunk in the metallic washer or cap B. I make the rod C shorter than the length of the body A, and make it fast by riveting or otherwise fastening or attaching its lower end to the metallic plate or disk D, which has a countersunk hole in its centre for the passage of the end of the rod C. The plate D is permitted to go to its place through a bore which I make in the lower end of the stopper of sufficient diameter, (see I, figs. 1 and 2.) This bore I now fill up with cork, India rubber, gutta percha, or wood, (see E, fig. 1,) or I fill it with shellac, wax, or any suitable gummy substance, (see F, fig. 2,) and thus prevent all contact of gases or fluids with the plate D or rod C; or I make the rod C with a screw, H, fig. 3, upon its lower end, to extend below the line J, and then screw a properly-shaped piece, G, of cork, or other suitable substance, upon it. In either of these three given forms of construction the principle is substantially the same.

The advantages of this improvement are as follows: The stopper can be instantly drawn by inserting through the eyelet of the rod C a small stick, nail, or piece of twine, doing away with the necessity of a cork-screw. Being supported at each end by the plates B and D, the stopper cannot be broken by ordinary use. No acids or gases can corrode it. It may be kept always attached to the bottle by a piece of twine, K, fig. 4, or by a chain, as seen at L, fig. 5. It will be the most economical of all stoppers, as it needs never to be broken in drawing, will not be thrown away, and may be used with care for many years.

I do not claim broadly a cord or stopper perforated by a metallic wire or rod, with washers riveted on to the ends, as I am aware that is old, as applied to some kinds of perfume bottles or ink bottles, and perhaps a few other specialties, but never in general use.

What I do claim as new, and as of my invention, is—

The bore I, figs. 1 and 2, the plug E, fig. 1, the plug F, fig. 2, the screw H and auxiliary piece G, fig. 3, in combination with the rod C and the plates B and D, and the body A, substantially as described and for the purpose set forth.

J. B. ALEXANDER.
